UNITED STATES PATENT OFFICE.

JOHN H. WAITE, OF BROCKTON, MASSACHUSETTS.

BOOT OR SHOE.

No. 918,615.

Specification of Letters Patent.

Patented April 20, 1909.

Application filed October 19, 1907. Serial No. 398,228.

To all whom it may concern:

Be it known that I, JOHN H. WAITE, a citizen of the United States, residing at Brockton, in the county of Plymouth and State 5 of Massachusetts, have invented a new and useful Boot or Shoe, of which the following is a specification.

It is often desirable to adjust the fastening of a boot or shoe over the instep without 10 interfering with the remainder of the lacing or buttons with which the shoe is fastened. In one kind of boot, the upper has been cut down below the instep so as to permit lacing farther down to give greater ease and 15 comfort at this point. This, however, as heretofore accomplished, results in an untidy appearance and has never been adopted for shoes which are intended to have a good appearance.

20 The principal objects of this invention are to provide a fastening means additional to that ordinarily used and independent thereof which can be adjusted over the instep so as to provide a construction in which, without 25 interfering with the ordinary lace or button fastening, the tightness of the boot or shoe over the instep can be varied at will, and at the same time to provide means whereby the shoe may be cut down farther 30 in the front than is ordinarily the case so that this additional fastening means may extend farther down toward the toe and at the same time give the foot a neat and attractive appearance. This is done by constructing 35 the quarters in such a way that two independent fastening devices may be applied to them, one at the lower and the other at the upper part, the latter being of any ordinary kind and the former preferably being a lacing 40 which can be adjusted at will while the upper fastening is undisturbed. This result is also preferably accomplished by a modification of the blank for the vamp by which the waste piece in the throat is utilized to 45 provide facings for the lower part of the vamp and these facings being integral with the vamp, reduce the thickness of the seam at the bottom of the instep by one layer of leather, thus giving additional comfort at a 50 point where much trouble is often experienced.

It will be seen, therefore, that another object of the invention is an economy secured by the utilization of the waste throat piece, 55 while another matter of economy can be taken advantage of in connection with this

invention by a modification of the form of the vamps, whereby small pieces may be used at the bottom thereof without in any way detracting from the appearance of the boot 60 or shoe but in fact enhancing it.

Further objects and advantages of the invention will appear hereinafter.

Reference is to be had to the accompanying drawing which shows a certain preferred 65 form of the invention and in which,

Figure 1 is a perspective view of a boot or shoe showing the invention as applied thereto when the main fastening is of the button variety. Fig. 2 is a perspective view 70 showing the invention applied to a Bal. shoe. Fig. 3 is a plan of a part of Fig. 1 on enlarged scale showing how the parts are connected together. Fig. 4 is a similar view of a shoe showing a new form of fastening device to take the place of the buttons, and Fig. 5 is a plan of the blank for the vamp 75 showing how the waste piece in the throat is utilized.

The shoe, as usual, comprises a vamp *a* 80 and two quarters *b*. Referring to Fig. 5, the blank *A* for the vamp is shown as having a portion cut out from one end toward its center to form a throat *A'* which is made of a shape similar to that ordinarily employed 85 in this art except that at the forward end *A*² of the throat, the same is extended forward to a greater degree and preferably terminates in two curves of large radius. Ordinarily, a waste piece is removed from this 90 throat, this waste piece extending nearly down to the point *A*² but usually somewhat short of the same on account of the shape of the die at this point. In carrying out the present invention, I prefer to utilize a portion of this waste piece by making a longitudinal slit at *A*³ therein extending down to a point somewhat forward of the point *A*², that is, the end of the slit *A*³ extends about 95 to the line which would be made by a continuation of the curves of the front part of the throat of the upper. A little material preferably is removed from the slit to fit the two pieces *A*⁴ and *A*⁴⁰ at the sides thereof for facings. A little material also may be removed between their outer edges and the adjacent edges of the main body of the upper, but of course the shape which these two pieces have may be varied within wide limits.

The quarters *b* may be made in the usual 110 way modified at the forward end sufficiently if necessary to correspond with the modified

form of the vamp. In assembling the parts, the quarters are secured to the vamps in the usual way except that the two facing pieces A^4 and A^{40} are secured over the forward edges of the vamps. This may be done in any desired way.

On account of the extension of the curves A^2 and the slit A^3 as has been described, the shoe may be made to open farther down than 10 is usually the case and eyelets c being applied to the facing and lower part of the quarters, a lacing d or other fastening device may be applied at this point. It will be seen that 15 this lacing extends over the instep from a point below that at which the shoe usually opens and that the lacing may be changed and adjusted to suit the convenience of the wearer, independently of the main fastening device which in Fig. 1 consists of a row of 20 buttons e extending upwardly from the top of the adjustable fastening d . In this form of shoe, the outside facing piece A^4 extends along the edge of the quarter as high as it is intended to have the adjustable fastening 25 extend and under the flap b' in which the button holes are located. The inside facing piece A^{40} preferably is of the same length and extends slightly above the point at 30 which the edge of the flap b' overlaps it. Thus the flap will conceal the ends of the 35 facings and the adjustable fastening or lacing d will be exposed to view and terminate in a bow just at the bottom of the flap b' . This results in a very neat appearance in addition to the advantages which have been 40 described above. An important feature of this construction is that in the seam at the bottom of the facing strips A^4 and A^{40} there is one less thickness of material than is the case where additional facing strips have to 45 be applied. This reduces the ridge always present at this point and materially adds to the comfort of the shoe. Moreover as has been set forth, this ridge is at a lower point where it will not cause as much discomfort 50 as when it is located well up on the instep, where it has to be in ordinary boots and shoes in order to secure an attractive appearance.

50 The invention may be carried out with additional economy; namely, the making of the quarters b out of a smaller piece of material and allowing them to terminate at a seam b^2 . When this is done an additional 55 piece of leather f is sewed to the lower end of each quarter. These additional pieces are of a general triangular shape and may be made of waste pieces which ordinarily cannot be used. On account of the adjust- 60 able lacing d or other fastening, the seam at b^2 does not detract from the appearance of the shoe as would be the case in the ordinary button, Bal., or Blucher shoe. This feature 65 of the invention while shown particularly in Fig. 3, is applicable to all forms of shoes

which may be made according to this invention.

In Fig. 2 also the invention is shown as applied to a Blucher shoe in which case the two flaps b^3 of the quarters are brought over the facing pieces A^4 and A^{40} so as to meet along the center and so as to cover the facing pieces in a manner similar to that described above with reference to the flap b' .

In Fig. 4 I have shown another way in 75 which the main fastening may be made, as a substitute for the button or lacing ordinarily used. This consists of a series of hooks g on one of the quarters and a series of eyelets h on the edge of the flap b' of the 80 other quarter, this flap preferably extending over in a manner similar to the button flap. A single lacing k is secured at one end near one of the eyelets or hooks and is then alternately threaded through the eyelets and 85 over the hooks as is indicated. By means of such a lacing the boot may be drawn up and tied in a very convenient way and as the lacing may remain threaded through the eyelets when the boot is taken off, it can be 90 applied to the hooks very readily.

While I have illustrated and described certain preferred forms of the invention, I am aware that many modifications may be made therein by any person skilled in the 95 art without departing from the scope thereof as expressed in the claims. Consequently, I do not wish to be limited to the particular forms of the invention shown but

What I do claim is:—

1. A boot or shoe provided with a vamp and two quarters, the quarters opening from the top to a point below the top edge of the vamp and having a main fastening means for the opening consisting of a row of buttons extending down substantially to the top of the convex part of the instep, and an independently adjustable fastening means extending downwardly on the top of the instep along said opening from the row of buttons to the bottom of the quarters, said second fastening means being connected with the quarters and with the vamp.

2. A boot or shoe comprising a vamp and quarters, the piece in the front of the vamp being left on the same and integral therewith, and being slit longitudinally so as to constitute two facings, said facings lying along the edges of the lower parts of the quarters and on the outside thereof, the upper part of the quarters extending over the upper ends of said facing, and means for securing said facings directly to the lower front edges of said quarters.

3. A boot or shoe comprising a vamp and quarters, the piece in the front of the vamp being left on the same and integral therewith, and being slit longitudinally so as to constitute two facings, said facings lying along the edges of the lower parts of the

quarters and on the outside thereof, the upper part of the quarters extending over the upper ends of said facings, means for securing said facings directly to the lower front edges of said quarters, a short lacing for securing the lower parts of the quarters and facings together, and a main fastening means for the quarters above the tops of said facings.

4. In a boot or shoe, the combination of a vamp having the piece in the throat thereof slit longitudinally and trimmed to form a facing integral with the vamp at the front of the throat thereof, a pair of quarters connected with the vamp and each consisting of two parts, one of said parts being of sub-

stantially a triangular shape and located at the front of the quarter, and in the front part of the throat of the vamp, the said facings being fixed to the front of said triangular pieces, a fastening means for said triangular parts and facings, and an additional fastening means for the main part of said quarters entirely above said triangular parts. 20

In testimony whereof I have hereunto set my hand, in the presence of two subscribing 25 witnesses.

JOHN H. WAITE.
